UNITED STATES PATENT OFFICE.

LEWIS J. EVANS, OF KIRKWOOD, NEW YORK.

ELEVATING DEVICE.

1,077,691.

Specification of Letters Patent.

Patented Nov. 4, 1913.

Application filed April 19, 1912. Serial No. 691,951.

To all whom it may concern:

Be it known that I, LEWIS J. EVANS, a citizen of the United States, residing at Kirkwood, in the county of Broome and State of New York, have invented new and useful Improvements in Elevating Devices, of which the following is a specification.

The invention relates to elevators and has for an object to provide a device for elevating articles or packages.

The invention embodies, among other features, a device that is particularly adapted for use in removing the ashes and cinders from a furnace, the mentioned ashes and cinders being received in a suitable container, conveniently placed beneath the furnace to receive the ashes and cinders from the ash pit thereof, the container being mounted on a suitable carriage, forming a part of my device, and which is movable to elevate the container and remove the same from beneath the ash pit to a convenient place of disposal.

In the further disclosure of the invention reference is to be had to the accompanying drawings, constituting a part of this specification, in which similar characters of reference denote corresponding parts in all the views, and in which:

Figure 1 is a side elevation of my device showing the carriage in lowered and normal position, a wall of the well and a portion of the frame of the device having been broken away to disclose the container arranged in normal position; Fig. 2 is a vertical transverse sectional view taken on the line 2—2 in Fig. 1, looking in the direction of the arrow; Fig. 3 is a side elevation of the device showing the container in elevated position, a wall of the well and a portion of the supporting frame having been broken away to disclose the interior arrangement and location of the device; Fig. 4 is a plan view of the structure disclosed in Fig. 3, the well door being shown in open position; and Fig. 5 is a fragmentary enlarged vertical sectional view taken on the line 5—5 in Fig. 4 to disclose the locking member for retaining the carriage in elevated position.

Referring more particularly to the views, I disclose a well 10 formed in the ground 11, a furnace 12 embodying an ash pit 13 being mounted on the surface of the ground 11 with the front portion of the ash pit 13 projecting beyond a wall 14 of the well 10. The

walls of the well 10 are preferably formed of concrete and a plate 15 is preferably mounted on the ground 11 or concrete, beneath the furnace 12, the plate being arranged between the surface of the ground 60 and the ash pit 13. A tongue is struck from the plate 15 to form an opening 16 therein, the mentioned tongue being bent downwardly to extend into the well 10 and constitute a guide plate 17, provided to guide the 65 contents of the ash pit when the same pass through the opening 16, arranged over the well 10.

Mounted on the base of the well 10 and supported by the upper ends of the walls 70 thereof is a rectangular supporting frame 18 and extending downwardly from an end piece 19 of the supporting frame 18 is a bar 20, bent inwardly at the bottom of the well 10 and curved upwardly to form a track 75 21, the free end of the bar 20 being rigidly secured to an end piece 22 of the supporting frame 18, the mentioned track 21 being arranged to conform to the curve described by the forward end of the carriage, where the 80 same operates over the track, the said track being arranged centrally in the well 10 as shown in Figs. 2 and 4.

A squared, transversely extending shaft 23 is journaled on the supporting frame 18 at 85 points adjacent the front end of the ash pit 13, and bifurcated ends 24 of arms 25 are rigidly secured to the shaft 23 adjacent studs 26, formed on the ends of the shaft 23, the mentioned studs 26 being mounted in the 90 supporting frame 18 to permit of swinging the arms 25 relatively to the said frame, the lower ends of the said arms having pivotal connection with a carriage 27 consisting of a frame 27^a provided with a base or platform 28, said frame terminating at the forward end in ears 29 having a roller 30 journaled thereon, the said roller being operable over the track 21 as shown in Figs. 1 and 2, the mentioned arms 25 being preferably connected to the carriage 27 by passing studs 31, extending laterally from the carriage, through openings in the lower ends of the mentioned arms, the point of pivotal connection of the arms 25 with the carriage 27 being offset and slightly in the rear of the vertical center of the carriage 27, so that when the carriage is elevated by advancing the same along the track 21, the carriage will, at all times, maintain a horizontal position, the said carriage 105 110

being movable to swing on the said arms 25 and to slide on the track 21, as will be readily understood. A flange 27^b is formed integral with the under side of the carriage frame 28 and projects outwardly. Upon this flange the arms 25 rest, thus preventing the forward tilting of the platform when the latter is supporting the loaded ash can. An operating lever 32 is rigidly secured to the squared shaft 23, the said operating lever being adapted to normally lie below the surface of the ground 11 and movable upwardly into a vertical position, thus rotating the shaft 23 and imparting a forward swinging movement to the arms 25 which, in turn, will cause the carriage 27 to be advanced along the track 21, it being readily understood that the arms 25 constitute a carriage frame for the carriage 27 and by means of which the carriage is operated over the track 21.

A container 33 is removably mounted upon the carriage 27, suitable guide members 34 and 35 being rigidly mounted on the upper side of the carriage 27 to aid in guiding the container 33 when the same is placed upon the carriage 27, the mentioned member 35 being provided at the rear end of the carriage 27 to prevent the container from being pushed or moved out of proper position on the carriage 27 so that when the carriage is in normal position the opening of the container will be immediately beneath the opening 16 in the plate 15, with the free end of the guide plate 17 projecting downwardly into proximity to the top of the container. Now assuming that the carriage 27, having the container 33 thereon, is in the position shown in Fig. 1, so that the contents of the ash pit will readily pass into the container 33 through the opening 16, when it is desired to remove the filled container and replace the same by an empty one, an upward pull is exerted on the free end of the operating lever 32, thus advancing the carriage 27 along the track 21 until the carriage reaches a position substantially in alignment with the surface of the ground 11 as shown in Fig. 3, the container 33 being now in a position to be easily removed from the carriage 27 and replaced by an empty container, after which the operating lever 32 is returned to the position shown in Fig. 1, thus returning the carriage 27 to normal position so that the new container will be arranged beneath the projecting end of the ash pit, thus permitting the contents of the ash pit to pass through the opening 16 and be guided by the plate 17 into the container. By offsetting the point of pivotal connection of the arms 25 with the carriage 27, as mentioned heretofore, the weight of the carriage and the weight of the container upon the carriage will be evenly balanced and supported by the roller 30 and the arms 25

so that when the carriage 27 is advanced along the track 21, the carriage will, at all times, remain in horizontal position, as mentioned heretofore.

In Fig. 5 I disclose a locking member 36, comprising a bracket 37 secured to the supporting frame 18 and having mounted to swing thereon a weighted dog 38, and a foot lever 39 having pivotal connection with the dog 38 and extending upwardly. When the carriage 27 swings upwardly one of the arms 25 engages the dog 38 and, in view of the pivotal connection of the dog with the bracket 37, the dog will permit the arm to pass upwardly beyond the dog, after which, when the upward pull is released on the lever 32, the arm 25 moving downwardly will be caught and supported in locked and rigid position by the dog 38 as will be readily understood, it being further seen that when a downward pressure is exerted on the free end of the foot lever 39, the dog 38 will be swung upwardly so as to disengage the same from the arm 25, thus permitting the carriage 27 to move gravitationally down on the track 21. As shown in Fig. 4, I preferably provide a plurality of locking members 36 mounted on the longitudinal sides of the supporting frame 18 to support both arms 25.

My device can be used in connection with various kinds of furnaces or stoves which, in their operation, produce a residue that must be periodically removed from the ash pits thereof and it will be readily apparent that my device can be used in connection with various power plants, mills or any other places where it is desired to elevate articles or packages from one plane to another.

When the carriage 27 is in lowered position within the well 10, the various parts of my device, with the exception of the foot lever 39, will be arranged within the well 10 and in order to prevent any one from falling into the well and to permit the operator of the furnace to properly attend to the same, I employ a closure 40 for the well 10, the mentioned closure being preferably made to swing from the supporting frame 18 and movable to close the opening of the well, a slot 41 being formed in the closure 40 to receive the upper end of the foot lever 39, said foot lever being arranged to extend exteriorly of the well, as mentioned heretofore.

It will be readily seen that by offsetting the points of pivotal connection of the arms 25 from the central vertical plane of the carriage 27, in the manner mentioned heretofore, an additional leverage is provided, said leverage being materially greater than if the points of pivotal connection of the arms with the carriage, were in the vertical plane of the carriage, thus greatly facilitating the operation of advancing and elevat-

ing the carriage on the track through the medium of the operating lever 32, the device being easily operable by any person of ordinary strength and ability.

5 Having thus described my invention, I claim:

1. In an elevating device, the combination with a supporting frame and depressed track, of a squared shaft journaled thereon, 10 arms rigidly secured to the said shaft and depending into proximity to said track, a carriage having pivotal connection with the said arms, a roller on the said carriage and movable over the said track, an operating 15 lever secured to the said shaft to rotate the same and operate the said arms to advance the said carriage along the said track, and locking members mounted on the said supporting frame and adapted to be engaged 20 by the said arms to retain the said carriage in stationary position relatively to the supporting frame.

2. In an elevating device, the combination with a supporting frame and depressed track, of a squared shaft journaled in said frame, arms rigidly secured to the said shaft and depending into proximity to said track, a carriage having pivotal connection with the said arms, a roller on the said carriage and movable over the said track, an operating lever secured to the said shaft to rotate the same and operate the said arms to advance the said carriage along the said track, and means on the said supporting frame for locking the said carriage in stationary position relatively thereto.

3. In an elevating device, the combination with a supporting frame and depressed track, of a squared shaft journaled on said frame, arms rigidly secured to the said shaft and depending into proximity to said track, a carriage having pivotal connection with the said arms, a roller on the said carriage and movable over the said track, and an operating lever secured to the said shaft to rotate the same and operate the said arms to advance the said carriage along the said track.

4. In an elevating device, the combination with a supporting frame, of a track thereon, a carriage frame mounted to depend from the supporting frame, a carriage mounted to swing on the carriage frame and movable over the said track, and means for operating the said carriage frame to advance the said carriage along the said track and swing the said carriage relatively to the said carriage frame as the said carriage is advanced along the said track so that the said carriage will 60 at all times assume a horizontal position.

5. In an elevating device, the combination with a supporting frame, of a track thereon, a carriage frame mounted to depend from the supporting frame, a carriage mounted to swing on the carriage frame and movable

over the said track, and means for operating the said carriage frame to advance the said carriage along the said track.

6. In an elevating device, the combination with a supporting frame, of a track mounted thereon and depending below said frame, a carriage frame mounted to swing on the supporting frame, a carriage mounted to swing on the said carriage frame, and means for sliding the said carriage along the said track and swinging the said carriage relatively to the said carriage frame.

7. In an elevating device, the combination with a well and a carriage movably mounted in said well, of a track in the said well leading from the bottom to the top thereof, and means for advancing the said carriage along the said track, the said carriage being at all times retained in horizontal position relatively to the said track.

8. In an elevating device, the combination with a well and a carriage movably mounted in said well, of a track mounted in the said well and having a portion inclined upward to the top thereof, and means for advancing the said carriage along the said track.

9. In an elevating device, the combination with a well and a carriage movably mounted therein, of a track in the said well having an upwardly curved portion, and means for advancing the said carriage along the said track.

10. In an elevating device, the combination with a supporting frame, of a base plate mounted to project beyond the end of the supporting frame, a guide plate struck from said base plate and depending beneath the supporting frame, a carriage frame mounted to swing on the supporting frame, a carriage having pivotal connection with the said carriage frame, a track beneath the said supporting frame and having an upwardly curved portion, the said carriage being mounted to turn on said carriage frame and to slide on said track, and means for operating the carriage frame.

11. In an elevating device, the combination with a supporting frame, of a track connected thereto and depending in a well, a carriage frame mounted on the said supporting frame and depending in the said well, a carriage having pivotal connection with the said carriage frame, and means for advancing the said carriage along the said track.

12. In an elevating device, the combination with a supporting frame, of a track mounted thereon and depending in a well beneath the supporting frame, a squared shaft journaled on the supporting frame, a carriage frame depending from the said shaft and extending into the said well, a carriage having pivotal connection with the said carriage frame, the said arms at the point of pivotal connection with the said

carriage being offset from the vertical plane of the carriage, a roller mounted on the said carriage and operable over the said track, and means connected with the said shaft for advancing and elevating the carriage along the track.

13. In combination a frame, a horizontally disposed carriage normally located below said frame, and means connecting said carriage and frame for causing longitudinal movement of the carriage to elevate the same while maintaining the carriage in horizontal position.

14. In combination, a well or pit in proximity with a furnace, a frame surrounding the upper perimeter of said well, a horizontally disposed platform suspended by swinging arms from said frame, means carried in

the frame and connected with said platform for elevating same to the upper level 20 of the well, substantially as described.

15. In combination with a well or pit, a horizontally disposed platform suspended by swinging arms within said well or pit; and means for elevating said platform to the 25 surface of the well or pit; said platform being maintained substantially horizontal throughout its travel, substantially as described.

In testimony whereof I affix my signature 30 in presence of two witnesses.

LEWIS J. EVANS.
